CIRCULAR KNITTING MACHINE ATTACHMENT

Edwin A. Copeland, Newton, N. C., assignor of one-third to Calvin C. Copeland, Newton, N. C., and one-third to Quality Hosiery Mills, Inc., Newton, N. C., a corporation of North Carolina

Application September 26, 1956, Serial No. 612,251

13 Claims. (Cl. 66—48)

This invention relates generally to an attachment for a circular independent needle knitting machine for changing the yarn on said machine. While this attachment is shown in connection with a machine manufactured by the Hemphill Company and known as their model SCOP, it should be obvious that this invention is not limited to use with this type of machine since the principles of the invention may be equally applicable in other circular knitting machines.

The parts with which the present invention is shown and described are disclosed in the patent to Lawson et al. No. 2,217,022 and the patent to St. Pierre No. 2,679,149. These patents disclose a circular knitting machine for knitting a stocking in which the leg thereof is reciprocatorily knit at both a main knitting station and an auxiliary knitting station simultaneously with a complete course being knit with each reciprocation of the needle cylinder to form a patterned leg. The top and foot of the stocking, on this type of machine, are knit with continuous rotary knitting and at the main knitting station only and the heel and toe pockets are knit reciprocatorily at the main knitting station only.

With the use of a cotton yarn throughout the stocking it is not necessary to change the yarn being fed during the heel and toe pockets but, with the ever increasing popularity of the synthetic stretch yarn, the demand has continued to increase for cotton patterned leg stocking having heel and toe pockets knit of a stretchable synthetic or nylon yarn such as Helanca. When knitting this type of stocking on the SCOP machine, the present practice is to knit the top, patterned leg and foot with the cotton yarn and the heel and toe with the Helanca yarn. After completing the widening operation in the toe pocket the machine has no means for changing the yarn before knitting the usual looper line and loopers rounds so that the Helanca yarn, from which the toe pocket is knit, must be used to form the looper line and loopers rounds. This practice causes the looper line, ordinarily formed by the knitting machine, to disappear upon the stocking being relaxed since the looper line is formed with a stretchable yarn. Thus, the cost of having the stocking looped is several cents per dozen higher than the cost of looping cotton stockings with a clear and distinct looper line. During the looping operation the loopers rounds are clipped off, in the usual manner, and discarded as waste and, since the Helanca yarn cost is greater than the cost of cotton yarn, the cost of producing this type of stocking is increased by the waste of the Helanca yarn used in the loopers rounds.

It is therefore a primary object of this invention to provide a yarn changing attachment for this type of knitting machine which provides a means for changing the yarns being fed to the needles during reciprocatorily knitting in

2

the widened courses of the toe pocket. This additional yarn change will enable the machine to form a clear and distinct looper line from a non-stretch fabric in the usual manner before completion of the toe pocket and before commencing the rotary knitting of the loopers rounds.

It is another object of this invention to provide a means for changing the yarn being knit during the widened portion of the toe pocket so that the loopers rounds may be knit with a less expensive yarn than the yarn from which the major portion of the toe pocket is knit.

It is still another object of this invention to provide a method of changing yarn during the knitting of a toe pocket requiring relatively few parts which may be added to the knitting machine in a matter of minutes and requires only minor changes to the knitting machine.

Some of the objects of the invention having been stated, other objects will appear as the description proceeds when taken in connection with the accompanying drawings, in which—

20 Figure 1 is a front elevation of a circular knitting machine with parts broken away;

25 Figure 2 is an isometric view of the auxiliary cam plate and showing the widening picks and their operating linkage and being taken substantially in the direction of the arrow marked 2 in Figure 1;

30 Figure 3 is an isometric view of the yarn change selector levers and being taken substantially in the direction of the arrow marked 3 in Figure 1;

35 Figure 4 is a side elevation of a typical stocking produced on this type of knitting machine and showing the usual toe opening after looping;

40 Figure 5 is a view of the foot and toe portion of the stocking shown in Figure 4 before the looping operation and as the stocking is knit on the knitting machine.

45 Referring to the drawings, the numeral 10 designates a housing or frame of the knitting machine supporting opposite ends of a rotatably main shaft 11. A sprocket wheel 12 supporting a pattern chain 13 and having a racking gear 14 integral therewith is mounted for rotation on the main shaft 11 and the racking gear 14 is suitably racked in a continuous and step by step manner during operation of the knitting machine. Upon suitable lugs, not shown, on the left-hand race (Figure 1) of the pattern chain 13 engaging the reading end of a pawl 17, a suitable racking mechanism, not shown, is released whereby the main shaft 11 is racked the desired number of steps according to the number of lugs or size of lugs placed on the pattern chain 13. The main shaft 11 has a main pattern drum 20 and a control drum 21 fixed thereon, both of which are rotated upon rotation of the main shaft 11 according to the desired pattern set up on the pattern chain 13.

50 The upper end of the frame 10 is provided with an extension 24 supporting a lower bed plate 25 in which the lower end of a conventional needle cylinder 30 is mounted for rotation or reciprocation and connected to the conventional driving mechanism of the knitting machine by suitable bevel gears, not shown. Respective main and auxiliary cam plates 32 and 33 partially surround the needle cylinder 30 and are vertically spaced above the bed plate 25 to support respective main and auxiliary stitch cam blocks 35 and 36. The main stitch cam block 35 is radially stationary while the auxiliary stitch cam block 36 is radially movable relative to the needle cylinder 30 and the radial movement is under control of suitable conventional pattern mechanism, not shown. The upper end of the needle cylinder 30 is surrounded by the usual

55 60 65 extension 24 supporting a lower bed plate 25 in which the lower end of a conventional needle cylinder 30 is mounted for rotation or reciprocation and connected to the conventional driving mechanism of the knitting machine by suitable bevel gears, not shown. Respective main and auxiliary cam plates 32 and 33 partially surround the needle cylinder 30 and are vertically spaced above the bed plate 25 to support respective main and auxiliary stitch cam blocks 35 and 36. The main stitch cam block 35 is radially stationary while the auxiliary stitch cam block 36 is radially movable relative to the needle cylinder 30 and the radial movement is under control of suitable conventional pattern mechanism, not shown. The upper end of the needle cylinder 30 is surrounded by the usual

sinker cap 40 and latch ring 41. The latch ring 41 is provided with a pair of throat openings, not shown, one of which is in substantial vertical alinement with the main stitch cam block 35 and the other in vertical alinement with the auxiliary stitch cam block 36 and both of which are provided with the usual yarn feeding fingers, not shown.

The yarn feeding fingers at the left-hand side of the knitting machine or the auxiliary feeding station are controlled and used only during the reciprocatory knitting in the pattern area by an auxiliary pattern yarn control drum, not shown, and in a conventional manner as shown and described in said Patent No. 2,217,022. The yarn feeding fingers at the main feeding station, at the right-hand side of Figure 1, are controlled during the pattern area of the sock by a main pattern yarn control drum 50 through a plurality of yarn change lever operating levers 52 (Figures 1 and 3) engaging the drum 50 or suitable cams placed thereon. The yarn change lever operating levers 52 engage the tail or free ends of corresponding yarn change levers 54 (Figure 3), the inner ends of which engage the yarn feeding fingers, not shown. A drum similar to the drum 50 and yarn change lever operating levers similar to the levers 52 are provided at the auxiliary feeding station and the two drums and levers comprise a secondary yarn changing means used to change the yarn feeding fingers at both feeding stations during knitting of the reciprocatorily knit patterned leg of the stocking.

The yarn feeding fingers at the main feeding station are also controlled, at times, by a primary yarn feeding means which includes the main pattern drum 20 and levers 60 and 61 engaging suitable cams placed thereon for changing the yarn feeding fingers during portions of the stocking other than the patterned area. The linkage for controlling the main yarn feeding fingers from the main pattern drum as well as from the main pattern yarn control drum 50 is clearly shown in Figure 39 in said Patent No. 2,217,022 while the mechanism for controlling the auxiliary yarn feeding fingers from the left-hand or auxiliary pattern yarn control drum and an auxiliary drum, not shown, on the main shaft 11 is clearly shown in Figure 40 of said Patent No. 2,217,022.

A third means for operating the yarn feeding fingers during the pattern portion of the stocking is shown and described in said Patent No. 2,679,149 and therefore only a brief summary of its operation and only the essential parts will be described in this application. The third means for operating the yarn fingers is provided in order to vary the color of yarn which may be used in the various solid color areas in the patterned leg of the stocking but this attachment is not effective in changing the yarn feeding fingers during reciprocatory single feed knitting in the heel and toe pockets. The pattern chain 13, on its right-hand race, has the usual lugs 65 suitably spaced according to the desired pattern and engageable by the reading end of a pivoted rocker arm 66, the free end of which is connected to the lower end of a connecting link 67. The upper end of the link 67 is connected to the lower end of a bell crank 70 pivoted on the knitting machine as at 71 and the upper end of which is suitably connected by a link 72 to the lower end of a lever 73 (Figures 1 and 3). The upper end of the lever 73 is fixed on one end of a yarn change selector shaft 74, rotatably mounted in the upper ends of a pair of upstanding supports 75, the lower ends of which are fixed on the knitting machine. The yarn change selector shaft is provided with suitable yarn change selector locking fingers 80 for engaging and actuating selected ones of the yarn change lever operating levers 52. The outer end of the shaft 74 has the upper end of a downwardly extending lever 85 fixed thereon, the lower end of which has one end of a connecting link 86 oscillatably mounted thereon. The opposite end of the link 86 is connected to a shaft, similar to the shaft 74, above the auxiliary yarn feeding fingers,

not shown, for controlling the yarn change levers and the yarn feeding fingers at the auxiliary feeding station and during the patterned portions of the stocking.

The auxiliary cam plate 33 supports, in addition to the auxiliary stitch cam block 36, a widening pick bracket 90 for supporting a pair of widening picks 91 and 92 in a conventional manner (Figure 2). The widening pick bracket 90 also oscillatably supports a widening pick throw-out shaft 95 which has conventional linkage thereon to render the widening picks 91 and 92 active or inactive according to a predetermined pattern. One end of the shaft 95 has one end of a lever 96 fixably secured thereto, the opposite end of which is fixed to the upper end of a widening pick control rod 97 which extends downwardly in Figures 1 and 2 and the lower end of which is adapted to ride on the control drum 21 and to be, at times, raised by suitable cams on the control drum 21. Raising of the rod 97, by cams on the drum 21, will rotate the shaft 95 and allow the widening picks 91 and 92 to move to operative position. The cams on the drum 21 thus provide a first means for starting a widening operation.

All of the parts heretofore described are conventional parts of the Hemphill model SCOP machine shown and described in said Patents No. 2,217,022 and No. 2,679,149 and it is with these parts that the present invention is adapted to operate. Referring to Figure 4, there is shown a typical Argyle type man's half hose H which is one of the many patterns that may be knit on this type of knitting machine and which includes a rotary knit top 100 which usually has an elastic yarn incorporated therein, a patterned leg 101 having solid colored areas 102 through 108, a reciprocatorily knit heel pocket 110, a rotary knit foot 111 and a reciprocatorily knit toe pocket 112.

The machine as described in said Patent No. 2,217,022, knits the top 100 by rotary knitting and single feed knitting at the main knitting station with the yarn feeding fingers being controlled by the primary yarn feeding means. The pattern 101, including the areas 102 through 108, is knit from yarns at both knitting stations with the yarn feeding fingers being controlled by the secondary yarn feeding means through the medium of the yarn change lever operating levers and pattern yarn control drums. The yarn feeding fingers are also controlled, during the pattern portion 101, by the third yarn feeding means through the link 67, pawl 66 and lugs 65 on the pattern chain 13. Upon completing the pattern portion 101, the machine switches into reciprocatory knitting to knit the heel pocket 110 and if a yarn change is desired in order to knit the pocket 110 from a different colored or different type yarn, such as a stretch yarn, the yarn change has to be effected by movement of the main pattern drum 20 since only the main stitch cams are in operation and the machine will be knitting single feed. Approximately half of the needles are selected to knit during the heel pocket and the number of needles knitting in each partial course are reduced in a narrowing operation by conventional narrowing picks, not shown. After completing the narrowing a widening operation is started by moving the widening picks 91 and 92 to operative position by a cam on the control drum 21 through the rod 97 to join the widened portion to the narrowed portion to form a suture line 115. Upon the heel pocket 110 being completed, the yarn, fed at the main feeding station, may again be changed to another color or to another type of yarn to knit the foot portion 111 by rotary single feed knitting by another movement of the main pattern drum 20.

After the desired length of foot has been knitted, the conventional machine, as equipped by the manufacturer, again shifts to reciprocatory knitting with the knitting still taking place at the main station only and if desired, the yarn may be again changed to knit the toe pocket 112 from a different color or different type of yarn than the yarn used in the foot 110. The yarn change, at the

start of the toe pocket 112, is effected by again moving the main pattern drum 20 another step to cause the yarn feeding fingers, not shown, to be changed. A narrowing operation then takes place in the same manner in which the narrowing operation in the heel pocket 110 was effected, followed by a widening operation to form a suture line 117 between the narrowed and widened portions in the toe pocket 112. In the widened portion of the toe pocket 112 operation of the widening picks 91 and 92 is started by a movement of the control drum 21 through the rod 97 and shaft 95. After the desired number of partial courses are made in the widened portion of the toe pocket 112 the machine again switches to rotary knitting and a course of loose stitches are formed to provide a looper line 121. After the looper line a few circular courses are knit at the main knitting station to form the usual loopers rounds 120 (Figure 5). The looper line 121 is provided to guide the operator in the looping operation for aligning the loose stitches on the points of the looping machine and the loopers rounds 120 are clipped off during the looping operation and discarded.

Thus, in the commercial machine and as shown and described in the two Patents No. 2,217,022 and No. 2,679,149, the only means shown and described for changing the yarn feeding fingers during single feed reciprocatory knitting in the heel and toe pockets 110 and 112 is by movement of the main pattern drum 20. Thus, if it is desired to use a different type of yarn in the heel and toe pockets, such as a stretch yarn, there is no provision, in the present machine, for changing yarn during the widened portion of the toe pocket 112 in order to knit the last few partial courses, the looper line 121 and the loopers rounds 120 from a non-stretch yarn.

The present invention requires only a relatively few parts and is simply applied without any major change to the mechanism of the knitting machine. These parts include a collar 125 (Figure 2) fixed on the rear end of the widening pick throw-out shaft 95 and which has the upper end of an L-shaped lever 126 fixed thereto. The horizontal portion of the lever 126 is provided with a pair of spaced collars 130 fixed thereon and a collar 131 loosely mounted between the collars 130. The collar 131 has one end of a link 132 fixed thereto, the medial portion of which extends behind the needle cylinder 30, in Figure 1, and the opposite end of which is provided with a pair of spaced collars 133 and 134 fixed thereon (Figure 3). The collars 133 and 134 confine one leg of a bent bracket 136, one end of which is loosely penetrated by the connecting link 132 and the opposite end of which is fixed on the lower end of the lever 85 (Figure 3). The only other change in the mechanism requires the addition of a special lug 140 on the right-hand side of the links of the pattern chain 13 and which special lug 140 is higher than the conventional lugs 65.

In the knitting of a hose as shown in Figures 4 and 5, the knitting machine operates in the usual manner in knitting the top 100, the pattern leg portion 101 and upon starting the narrowed portion of the heel pocket 110 the yarn is changed from the cotton yarn with which the top 100 and the pattern portion 101 was knit and a stretchable yarn is introduced to knit the heel pocket 110. The yarn is changed at this point by a conventional movement of the main pattern drum 20 and after the desired number of narrowed partial courses are knit in the heel pocket 110 a conventional movement of the control drum 21 is effected in order to render the winding picks 91 and 92 operative and start a widening operation to complete the heel pocket 110. Upon completion of the heel pocket 110 a yarn change is again effected by movement of the main pattern drum 20 during the last partial course of the heel pocket 110 and as the knitting machine goes into rotary knitting to knit the foot portion 111 with cotton yarn.

The foot portion 111 is then knitted by rotary knitting

in the usual manner for the desired number of courses, depending upon the size foot desired. The toe pocket is then started in the conventional manner and the yarn change is effected by another movement of the main pattern drum 20 so that the narrowed portion of the toe pocket 112 will be knit from a stretch yarn. After the desired number of narrowed partial courses have been knit the usual or conventional practice is to cause the widening picks 91 and 92 to start operating by movement of the control drum 21 but, if the widening picks 91 and 92 are started in this manner there will not be a movement of the control drum 21 and the main pattern drum 20 when it is desired to change the yarn before completing the widening operation in the toe pocket 112. In order to preserve this move of the control drum 21 and pattern drum 20 to change yarns, at a later time, the widening picks 91 and 92 are moved into operative position at this time by the lever 66 engaging the extra high special lug 140 of the pattern chain 13. Movement of the lever 66 will lower the rod 67, in Figure 1, move the bell crank 70 in a clockwise direction, move the shaft 74 in a counter-clockwise direction and pull the connecting link 132 from left to right, in Figure 1. As the link 132 is moved from left to right the shaft 95 will be moved in a counter-clockwise direction and through the conventional intervening connections release the widening picks 91 and 92 to operate in the widened portion of the toe pocket 112. The high lug 140 on the chain 13 thus provides a second means for starting a widening operation.

After substantially all of the widened partial courses in the toe pocket 112 have been knit with the stretch yarn or until only approximately four partial courses are left in the widened portion of the toe pocket, a yarn change is effected, by movement of the main pattern drum 20 and control drum 21, this movement being the one that was reserved previously by effecting operation of the widening picks 91 and 92 from the lug 140 on the pattern chain 13. Thus, the stretch yarn is removed at the line indicated at 150, in Figures 4 and 5, and the remaining few or, in this case, four partial courses in the widened portion of the toe pocket 112 are knit from the cotton yarn.

After completion of the toe pocket 112 the conventional mechanism on the knitting machine switches the needle cylinder 30 to rotary motion and then causes the needles to draw extra long or loose stitches for one complete course to form the looper line 121. Then a few complete courses, usually sixteen, are knit to form the usual loopers rounds 120 to aid the looper in placing the knitted hose on the points of the looping machine. After the toe pocket has been looped, in the conventional manner along the line 151 in Figure 4, the loopers rounds 120, clipped off during the looping operation, are discarded as waste.

It is thus seen that I have provided a novel means for changing yarns before completion of the toe pocket of a stocking and during the widening operation which provides a clear and distinct looper line and wherein the loopers rounds, which are wasted after the looping operation, may be knit from a less expensive yarn than the expensive yarn used in the toe pocket. The changing of the yarns during the widened courses of the toe pocket being made possible by slight modification of the machine so that the widening picks may be rendered operative by a movement of the pattern chain.

In the drawings and specification there has been set forth a preferred embodiment of the invention and, although specific terms are employed, they are used in a generic and descriptive sense only and not for purposes of limitation, the scope of the invention being defined in the claims.

I claim:

1. In a circular independent needle knitting machine

having yarn feeding fingers for feeding yarns to said needles, a primary yarn changing means, a secondary yarn changing means, a third yarn changing means and a first means for starting a widening operation; the combination therewith of a second means for starting a widening operation, and linkage means connecting said third yarn changing means and said second means for starting a widening operation.

2. In a circular independent needle knitting machine having yarn feeding fingers for feeding yarns to said needles, a pattern chain, a primary yarn changing means, a secondary yarn changing means, a third yarn changing means under control of said pattern chain and a first means for starting a widening operation; the combination therewith of a second means for starting a widening operation also under control of said pattern chain, and means interconnecting said third yarn changing means and said second means for starting a widening operation.

3. In a circular independent needle knitting machine having a pattern chain, a main pattern drum, a control drum, yarn feeding fingers for feeding yarns to said needles, a primary feeding finger changing means controlled by said main pattern drum, a secondary feeding finger changing means, operation of said secondary feeding finger changing means being under control of said primary feeding finger changing means, a third feeding finger changing means under control of said pattern chain and a first means for starting a widening operation under control of said control drum; the combination therewith of a second means for starting a widening operation also under control of said pattern chain, and linkage connecting said third feeding finger changing means and said second means for starting a widening operation.

4. A widening pick control system for a circular independent needle knitting machine having a pattern chain and a control drum controlled by said pattern chain which includes; the combination of first widening pick control linkage operated by said control drum and a second widening pick control linkage operated by said pattern chain.

5. A widening pick control system for a circular independent needle knitting machine having a pattern chain, a control drum controlled by said pattern chain and a widening pick control which includes; the combination of first means for controlling said widening pick control operated by said control drum and second means for controlling said widening pick control operated by said pattern chain.

6. A widening pick control system for a circular independent needle knitting machine having a pattern chain, a main pattern drum, a control drum controlled by said pattern chain, primary yarn changing means operated by said main pattern drum, secondary yarn changing means under control of said primary yarn changing means, third yarn changing means controlled by said pattern chain and a widening pick control which includes; the combination of first means for controlling said widening pick control operated by said control drum and second means for controlling said widening pick control operated through said third yarn changing means.

7. In a circular independent needle knitting machine having a pattern chain, a main pattern drum, a control drum, said pattern drum and control drum both controlled by said pattern chain, a primary yarn changing means controlled by said main pattern drum, a secondary yarn changing means to produce a pattern stocking leg, second means being under control of said primary means, a third yarn changing means operating directly upon said second yarn changing means, said third yarn changing means being controlled by said pattern chain, widening picks, first widening pick control means controlled from said control drum; the combination therewith of second widening pick control means for operating said widening picks through said third yarn change means

and from said pattern chain, and linkage connecting said third yarn change means and said widening picks.

8. In a circular independent needle knitting machine having a pattern chain, first lugs on said pattern chain, a main pattern drum, a control drum, a main shaft on which said pattern drum and said control drum are mounted, movement of said main shaft controlled by said first lugs on said pattern chain, a primary yarn changing means controlled by movement of said main pattern drum, a secondary yarn changing means to produce a patterned stocking leg, said second means being under control of said primary means, a third yarn changing means operating directly upon said second yarn changing means and said third yarn changing means controlled by said first lugs on the pattern chain, widening picks, widening pick control means controlled at predetermined times from said control drum; the combination therewith of linkage connecting said third yarn change means and said widening pick control means and second lugs on the pattern chain for operating said widening pick control at predetermined times through said linkage connecting the third yarn change means.

9. In a circular knitting machine having a needle cylinder, needles vertically movable in said needle cylinder, a main feeding station and an auxiliary feeding station, a pattern chain, widening picks, a first yarn control means for controlling yarns fed to the needles at said main feeding station, a second yarn control means at both knitting stations for controlling the yarn fed to the needles to produce a patterned leg stocking, a third yarn control means at both knitting stations for controlling the yarn changing during the patterned leg portion and being under control of the pattern chain, a yarn control drum for controlling the operation of the widening picks during the formation of the heel and toe pockets; the combination therewith of an auxiliary control for the widening picks operated by the main pattern chain.

10. In a circular knitting machine having a needle cylinder, needles vertically movable in said needle cylinder, a main feeding station and an auxiliary feeding station, a pattern chain, widening picks, a first yarn control and means for controlling yarns fed to the needles at said main feeding station, a second yarn control means at both knitting stations for controlling the yarn fed to the needles to produce a patterned leg stocking, a third yarn control means at both knitting stations for controlling the yarn changing during the patterned leg portion and being under control of the pattern chain, a yarn control drum for controlling the operation of the widening picks during the formation of the heel and toe pockets; the combination therewith of linkage connecting the widening picks and the third yarn control means and an auxiliary control for the widening picks operated through the third yarn control means by the main pattern chain.

11. A method of knitting a circular knit stocking having rotary knit portions knit of a first yarn and reciprocatorily knit heel and toe pockets knit from a second yarn; comprising the steps of knitting the complete narrowed and widened portion of said heel pocket from the second yarn, knitting the complete narrowed portion of the toe pocket from said second yarn, knitting only part of the widened portion of the toe pocket from said second yarn and knitting the remainder of the widened portion of the toe pocket from said first yarn.

12. A method of knitting a circular knit stocking having rotary knit portions and reciprocatorily knit heel and toe pockets; comprising the steps of knitting the rotary knit portions with a non-stretch yarn, knitting the complete narrowed and widened portion of said heel pocket from a stretchable yarn, knitting the complete narrowed portions of the toe pocket from said stretchable yarn, knitting only part of the widened portion of the toe pocket from said stretchable yarn and knitting the re-

mainder of the widened portion of the toe pocket from said non-stretch yarn.

13. A method of knitting a circular knit stocking having a rotary knit top, reciprocatorily knit patterned leg, reciprocatorily knit narrowed and widened heel pocket, rotary knit foot, reciprocatorily knit toe pocket and rotary knit loopers rounds; comprising the steps of knitting the rotary knit top, reciprocatorily knit patterned leg, rotary knit foot, part of the reciprocatorily knit widened portion of the toe pocket and loopers rounds

5

10

from a non-stretch yarn, and knitting the complete narrowed and widened portions of the heel pocket, the complete narrowed portion and only part of the widened portion of the toe pocket from a stretchable yarn.
